UNITED STATES PATENT OFFICE.

HARRY E. KAUP, OF BELLEVUE, AND RICHARD J. WILCOX, OF CARNEGIE, PENNSYLVANIA, ASSIGNORS TO PRESSED STEEL CAR COMPANY, OF PITTSBURGH, PENNSYLVANIA, A CORPORATION OF NEW JERSEY.

DISCHARGE-DOOR-OPERATING MECHANISM.

1,390,357.

Specification of Letters Patent. Patented Sept. 13, 1921.

Application filed May 16, 1921. Serial No. 469,807.

To all whom it may concern:

Be it known that we, HARRY E. KAUP and RICHARD J. WILCOX, citizens of the United States, residing in Bellevue and Carnegie, respectively, in the county of Allegheny and State of Pennsylvania, have invented certain new and useful Improvements in Discharge-Door-Operating Mechanism, of which the following is a specification.

10 This invention relates to railway dump cars and particularly to that type of dump car in which the discharge doors are supported and operated by a bodily movable shaft. Heretofore it has been found that, 15 in dump cars of the above type in which the discharge doors do not extend to the end of the car and have the discharge door operating shaft extended some distance beyond the end door of the car, the shaft, 20 when it is being operated to open or close the doors, will not move parallel with the longitudinal center line of the car and will thus cause the shaft and associated parts to become inoperative.

25 An object of the present invention is to provide means whereby a bodily movable discharge door operating shaft that extends some distance beyond the end door of a car, is caused to move parallel with the longitudinal center line of the car as the shaft is being operated to open or close the discharge doors.

This and other objects will be apparent from the following description.

30 Referring to the drawings in which like reference characters refer to like parts, Figure 1, is a plan view of a portion of a car embodying the invention; Fig. 2, is a side elevational view of the same; Fig. 3, is a 35 cross sectional view of a portion of the car taken on the line 3—3 of Fig. 1; Fig. 4, is an enlarged detail longitudinal sectional view taken on the line 4—4 of Fig. 1 and Fig. 5, is an enlarged detail cross sectional view taken on the line 5—5 of Fig. 2.

40 There are various types of cars to which the hereinafter described mechanism may be applied, some of which are illustrated in Patent No. 791,348, granted May 30, 1905, 45 to Charles A. Lindstrom and John F. Streib. For illustrative purposes, a car of the hopper type has been shown in the drawings, which has an underframe comprising a center sill 1, end sill 2, bolsters 3

and intermediate transverse members 4, all 55 of which may be of any desired construction and suitably connected together. The body of the car comprises sloping end floors 5 and side walls 6 which floors and walls are suitably connected with the underframe 60 and with each other. The lower edge portions of the side walls and sloping floors together with the center sill and transverse members 4, define discharge openings on both sides of the longitudinal center line 65 of the car, each of which openings is adapted to be closed by a door 7, which is preferably hinged along its inner edge portions to bracket members suitably connected with the center sill 1. The underframe extends 70 a considerable distance beyond the end of the body of the car and forms a platform 8. To operate the discharge doors 7 and for the purpose of supporting such doors in their closed positions, shafts 9 are provided. 75 These shafts are rotatably and slidably mounted in slots formed in members 10 which are preferably secured to the end sill 2, bolsters 3 and transverse members 4 of the underframe. To each of these shafts are 80 preferably secured a plurality of spirally grooved drums 11, to each of which one end of a chain 12 is connected, the other end of the chain being connected with the outer or free edge of the door preferably through 85 the medium of a member 13 which is secured to the door. This member 13 is provided with a serrated shoe portion 14 which is adapted to engage with a serrated roller 90 secured to the shaft, which roller may be 95 made integral with the spirally grooved drum 11.

Each of the shafts 9 extend a considerable distance beyond the end door 7 and a sufficient distance beyond the support for the end portion of the shaft to apply a lever or other suitable operating device. Intermediate the support for the end portion of the shaft and the end door 7, the shaft is provided with a serrated or toothed member 100 16 which is adapted to engage with a serrated or toothed member 17 secured to the underside of the platform 8 and located preferably above the shaft, which members, when in such engagement and the shaft is 105 rotated, coöperate to move said shaft bodily in directions transversely of the car. Intermediate the support for the end portion

of the shaft and the end door 7 and preferably near the members 16 and 17, a chain 18 or any other suitable connection is provided one end of which is attached to the 5 shaft and the other end to a member 19 secured to the underside of the platform 8. When the shaft is being rotated in the door closing direction this chain 18 will wind upon the shaft and will assist in causing 10 said shaft to move out of notches 20 formed in the bearing members 10.

Assuming the discharge doors to be in their closed positions and it is desired to open them, the operations are as follows: 15 the operator, by the use of a suitable lever or device rotates the shaft 9 in the direction as indicated by the arrows in Figs. 3 and 5 which causes the serrated shoe portions 14 and rollers 15 and the members 16 and 17 20 to coöperate to move the shaft outwardly a sufficient distance as to be substantially free of the doors, at which time the shaft drops into the notches 20 and the doors are permitted to open by gravity, the shaft rotating 25 freely in such notches as the doors move to open positions. It will be noted that as the shaft moves into the notches 20 the member 16 moves out of engagement with the member 17 to a position as shown in dot and dash 30 lines in Fig. 5, and will thus permit the shaft to rotate freely in the notches 20. To close the doors the operator rotates the shaft 9 in a direction opposite to that indicated by the arrows in Figs. 3 and 5 which causes 35 the chains 12 to wind upon the drums 11 and the chain 18 to wind upon the shaft until such time as the chains 12 have raised the doors to such a position that the outer end portion of the serrated shoe 14 is slightly 40 above the serrated portion of the rollers 15 at which time a continued rotation of the shaft and the winding of the chain thereon creates tension on the chains 12 and 18 and causes the shaft to move bodily out of the 45 notches 20. As the shaft moves out of the notches 20 the rollers 15 will engage with the shoe portions 14 and the member 16 will engage with the member 17 and a continued rotation of the shaft will cause said rollers 50 and shoes and the members 16 and 17 to coöperate and cause said shaft to move inwardly a sufficient distance to close the doors and to support them in closed positions.

It will be apparent to those skilled in the 55 art to which this invention appertains that many changes may be made in the details and arrangement of the parts forming the invention without departing from the spirit and scope of the appended claims.

Having thus described the invention what 60 we claim as new and desire to secure by Letters Patent is:—

1. In a dump car, a discharge door, a 65 bodily movable shaft for operating said door, and means for moving said shaft

bodily, said means comprising a flexible connection from said shaft to said door and a flexible connection from said shaft to a stationary part of said car.

2. In a dump car, a discharge door, a 70 bodily movable shaft for operating said door, and means for moving said shaft bodily in one direction, said means comprising a flexible connection from said shaft to said door, and a flexible connection from 75 said shaft to a stationary part of said car.

3. In a dump car, a discharge door, a bodily movable shaft for operating said door, and means for moving said shaft bodily, said means comprising a serrated 80 member secured to a stationary part of said car and serrated members on said shaft adapted to engage said members, to move said shaft bodily in one direction and means independent of said serrated members for 85 moving said shaft in the opposite direction.

4. In a dump car, a discharge door, a bodily movable shaft for operating said door, and means for moving said shaft bodily in one direction said means comprising 90 a flexible connection from said shaft to said door and a flexible connection from said shaft to a stationary part of said car, and means for moving said shaft bodily in both directions, said means comprising 95 inter-engaging serrated members mounted on said car and said shaft.

5. In a dump car, a discharge door, a bodily movable shaft for operating said door, said shaft being of greater length than 100 said door, flexible and serrated means between said door and shaft for moving said shaft bodily and flexible and serrated means independent of said door for moving said shaft bodily, both of said means being 105 adapted to move said shaft parallel with the longitudinal center line of the car.

6. In a dump car, a hinged discharge door, a bodily movable shaft for operating said door, a flexible connection between said 110 shaft and door and a flexible connection between said shaft and a stationary part of said car, said connections being adapted to cause said shaft to move bodily.

7. In a dump car, a hinged discharge door, 115 a bodily movable shaft for operating said door, said shaft extending beyond said door, connection between said shaft and door for moving said shaft bodily, and means independent of said door for causing said shaft 120 to move substantially parallel with the longitudinal center line of the car.

8. In a dump car, a discharge door, a bodily movable shaft for operating said door, a flexible connection from said shaft 125 to said door for raising said door and for moving said shaft bodily and a flexible connection between said shaft and a stationary part of said car for moving said shaft bodily.

9. In a dump car, a discharge door, mecha- 130

- nism for operating said door, said mechanism comprising a lifting shaft, and a flexible connection therefrom to the door and a flexible connection therefrom to a stationary 30
5 part of said car, said shaft being movable by said connections into supporting position when the door is raised. 35
10. In a dump car, a discharge door mechanism for operating said door, comprising a lifting shaft mounted to move bodily, a flexible connection extending therefrom to the door and a flexible connection therefrom to a stationary part of the car, said connections being adapted to move said shaft 40
15 bodily. 45
11. In a dump car, a discharge door, mechanism for operating said door, said mechanism comprising a lifting shaft arranged to support the door when the door is raised, a flexible connection between said shaft and door, a flexible connection between said shaft and a stationary part of said car, said connections being adapted to move said shaft in the door supporting direction when the door 50
20 is raised. 25
12. In a dump car, a discharge door, mechanism for operating said door, said mechanism comprising a lifting shaft, flexible connections whereby said shaft is moved auto-

matically into supporting position under the door when the door is closed, one of said connections being secured to said shaft and to said door and the other of said connections being secured to said shaft and a stationary part of said car. 30

13. In a dump car, a discharge door, a bodily movable shaft for operating said door, said shaft being movable under said door, and means for moving said shaft bodily, said means comprising a flexible connection from said shaft to said door and a flexible connection from said shaft to a stationary part of said car. 40

14. In a dump car, a discharge door, a shaft for operating said door, said shaft being movable bodily across the path of the free edge of said door and means for moving said shaft bodily, said means comprising a connection from said shaft to said door and a connection from said shaft to a stationary 50
part of said car. 55

In testimony whereof we affix our signatures in the presence of two witnesses.
